SETTER FOR SNAP FASTENERS

Julius Gualtieri, Brooklyn, N. Y., assignor to
 Edwin B. Stimpson Company, Brooklyn, N. Y.,
 a corporation of New York

Application May 16, 1934, Serial No. 725,888

8 Claims. (Cl. 218—6)

The present invention relates to rivet setting machines and more especially to a machine for setting sockets and caps for snap fasteners.

Snap fasteners usually comprise two members, 5 namely, a snap socket which passes through the material and a cap on the other side of the material into which the socket is expanded to anchor the cap in place and to hold the socket securely riveted in place in the material. Snap 10 fasteners of this kind are common as glove snaps and as many other articles of commerce.

Heretofore in the art, it has been customary to feed the parts by hand to a rivet setter which was adapted to apply pressure to expand the 15 socket within the cap and hold the parts securely locked in place.

The present invention comprises an automatic machine which for each operation of the machine automatically feeds a socket member and a fastener cap and then applies pressure to expand the fastener within the cap. The cycle of 20 operations is such that a socket is positioned at the work anvil. The goods, having an opening 25 perforated therein to receive the stem of the fastener, is slipped over the socket and the machine is then operated. The operation of the machine feeds a cap over the portion of the socket extending through the goods, and applies 30 pressure to expand the stem of the socket within the cap. It, therefore, will be seen that each 35 operation of the machine results in a completed fastener comprising a socket and a cap being automatically applied to the goods.

The feed mechanism of the machine comprises 40 a novel construction for feeding both the caps and the sockets. The sockets are small hollow stemmed tubular members shaped somewhat like a head gear known as a "stove pipe" hat. The feed mechanism for the sockets comprises a feed drum and a feed ring spaced slightly from the 45 face of the drum, so that the socket members leave the feed drum with the stems passing through exit slots in the feed ring. The stems of the sockets extend inwardly toward the machine. This is the opposite position usually provided for feeding articles of this shape and the reversal of the feed position is due to the novel feed ring spaced from the face of the feed drum.

The caps comprise hollow members being 50 rounded or oval on one side and provided with an opening on the other side. The feed passage-ways provided in the edge of the feed drum for the caps are constructed with conical projections located in the central part of each feed passage-way. The facing adjacent the cap feed drum is provided with an annular groove opposite the path of the said projections. A cap falling into a passageway with the back of the cap toward the outer face of the feed drum will be blocked 55 from going through the passageway by the coni-

cal projection, but any cap falling into a passageway with the back of the cap toward the facing will slide downward through the passageway and the conical projection will pass into the opening in the cap and gravity will cause the cap to slide over the face of the conical projection and out into a feed channel. This arrangement permits the feed of the caps in such manner that all of the tops of the caps face in one direction in the cap runway so that the caps come 10 right side up into proper place for further operations.

The runway or feed chute for the sockets is arranged to deliver sockets adjacent a feed slide, which in the operation of the machine 15 moves sockets one at a time from the end of the chute forward over an anvil at the work station. As soon as the slide has moved a socket to position over the anvil, a holding pin rises through the anvil and enters the opening in the socket, 20 thereby positioning and holding the socket in place at the work station when the feed slide retreats. The caps are fed downward one at a time into a spring armed cup located directly over the anvil on which the socket has been 25 positioned. When the operator has placed the material over the socket, so that the socket extends over an opening in the material and the machine is set into operation, a plunger drives the cap through the spring cup with the opening in the 30 cap downward so that it covers the end of the socket and the plunger continues its downward travel to apply pressure which expands the socket 35 within the cap.

During the setting operation, the socket holding pin remains within the socket, but since this pin is supported by a yielding spring, the holding pin moves downward under the influence of the pressure applied through the plunger. The spring arm cup is constructed to descend with the setting plunger until the cap held in the cup has substantially reached the end of the socket, thereby obviating any danger of the cup being displaced during the setting operation. The holding pin is withdrawn when the operation is 45 completed and the work may be removed from the machine.

Other and further objects of the present invention will in part be obvious and will in part 50 be pointed out hereinafter in the specification following by reference to the accompanying drawings which illustrate the preferred form of the present invention.

It is realized that the invention may be practiced by constructions other than those specifically illustrated herewith, so, therefore, the specific disclosure herewith is to be understood as 55 illustrative and not in the limiting sense.

Fig. 31 illustrates a sectional view of a completely assembled snap fastener socket and cap

and illustrates the finished product produced by the present invention.

Referring to the drawings and more especially to Fig. 1, a pedestal frame 1 carries an electric motor 2 which is the driving unit for the device. An operating pedal 4 is pivoted in the base of the pedestal frame and is normally held in raised position by a coil spring 5 anchored at one end to the pedestal frame and at the other end to the pedal. An adjustable stop 6 limits the upward movement of the pedal. A head frame 7 is securely mounted on the pedestal frame 1 and is the main support for the operating mechanism. The electric motor 2 is connected by a belt 8 with a weighted drive pulley 9 to rotate the pulley in the direction of the arrow A (Fig. 1). A clutch link 10 extends from the pedal 4 to the clutch mechanism whereby the operator upon depressing the pedal 4 causes the clutch mechanism to engage the driving pulley 9 with the operating mechanism.

Referring now to Figs. 2, 3, and 4, the clutch link 10 is provided with an offset 11 that engages a pin 13 on an arm 12 of a bell crank lever 14 which is connected by a pin 15 to the clutch cam bolt 16. The inward travel of the cam bolt 16 is controlled by the stop plate 23 which extends into a groove in the side of the cam bolt 16. This arrangement also prevents the cam bolt from rotating. The pin 15 operates in a slot in the bell crank 14 so that when the clutch link 10 is pulled downwardly by the pedal 4, the bell crank 14 pulls the cam bolt 16 outwardly beyond the path of movement of a clutch bar 17 (Fig. 4). This clutch bar 17 slides under the influence of a spring 18 until the operating end of the clutch bar comes into the path of a clutch stud 19 which is carried by the hub of the weighted drive pulley 9. This drive pulley normally rotates loosely on a bearing sleeve 20 on a main shaft 21. The clutch bar is mounted in a collar 22 rigidly fastened to the main shaft 21. When the head of the clutch bar 17 slides inwardly into the path of the clutch stud 19, the engagement of this stud 19 with the end of the clutch bar 17 drives the main shaft from the drive pulley 9, thereby causing the mechanism to operate. When the cam bolt 16 is at normal position, a cam 24 (Fig. 3) on this bolt 16 engages a cam 25 on the clutch bar 17 and withdraws the clutch bar from engagement with the clutch stud 19 and the operating cycle stops. A coiled spring 26 connected with the arm 12 of the bell crank 14 causes the cam bolt 16 to return to normal position as soon as it has been withdrawn by the pedal 4. A spring 27 (Fig. 2) normally pulls the upper end of the clutch link into position over the inner end of the pin 13 which extends inwardly from the arm 12 of the bell crank (Fig. 2). The upper end of the clutch link 10 is attached to a slotted link 28 which is connected with a crank arm 29 on a slide operating shaft 30. This shaft 30 oscillates from its normal vertical position (Fig. 2) when the machine operates. When the clutch link 10 is moved downward by the depression of the pedal 4, the offset 11 on the arm 12 engages the inner end of the pin 13 and swings the bell crank 14 to withdraw the bolt 15 from its normal position. This permits the spring 18 (Fig. 4) to move the clutch bar 17 inward to engage the clutch stud 19, thereby causing the machine to operate. When the machine operates, the upper end of the crank arm 29 swings toward the left (Fig. 2) and pulls the offset 11 on the link 10 from its position over the inner end 75

of the pin 13, even if the pedal 4 is held depressed. The spring 26 then swings the bell crank 14 to cause the cam bolt 16 to move inward so that the cam 24 on the end thereof comes into the path of the cam 25 on the clutch bar 17 and the continued rotation of the main shaft 21 causes the engagement of these cams 24 and 25 to withdraw the clutch bar 17 from the clutch 19. From the foregoing, it will be noted that the machine will make but one single cycle of operations, each time the pedal is depressed regardless of whether or not the operator lifts his foot promptly after he has depressed the pedal 4. When the shaft turns to swing the crank arm 29 to the right the spring 27 returns the offset 11 to normal position over the inner end of the pin 13.

The main shaft 21 carries a brake drum 32 (Figs. 2 and 3). A brake shoe 34 sets solidly against this brake drum 32 but is effective on only a part of the brake drum. The brake drum 32 is provided with a slight high spot adjacent the angular position where the clutch bar 17 is disengaged from the clutch stud 19. This slight high spot on the brake drum comprises a very simple expedient for applying the brake effect at the proper moment, so that as soon as the clutch is opened, the main shaft 21 stops rotating with the parts at the end of an operating cycle.

The brake drum 32 carries a heavy stud 35 (Figs. 2, 6, and 8), upon which a thrust link 36 is mounted. This thrust link 36 is connected at its upper end with a main lever 37. The connection between the thrust link and the main lever comprises an adjustable eccentric stud 38, which is held in adjusted rotative position by the clamp nut 39. The adjustable eccentric stud 38 is for the purpose of adjusting the working zone of the main lever 37 as will be explained later. The main lever 37 is pivoted on a short shaft 40 (Figs. 10 and 11) which rotates in bearing arms 41 and 42 (Figs. 3, 4, and 11) on the head frame 7. The forward end of the main lever 37 is connected by links 44 with a plunger 45 that reciprocates in bearings 46 and 47 in the front portion of the head frame 7 and carries a setting head 48 adapted to cooperate with an anvil 49 (Figs. 6 and 8) to set caps in position over fastener sockets. The anvil 49 is removably mounted in the head frame 7 by a locking screw 50 (Fig. 5).

A socket holding pin 51 is mounted to reciprocate through the center of the anvil 49. This holding pin (Figs. 5, 7, and 9) is guided by a head sleeve 52 and is urged upwardly by a spring 54 mounted in an adjustable screw cup 55. The head sleeve 52 is adapted to reciprocate in the frame 7 and is stopped in its upward movement by a stop lever 56 mounted on a rocker arm 57 which is pivoted on a rocker shaft 58 and is provided with an anti-friction roll 59 that is held in engagement with a rocker arm cam 60 on the main shaft 21 by the operation of the spring 54. The distance the holding pin 51 extends through the anvil 49 may be adjusted by an adjustable stop 61 carried by the rocker arm 51 and operative upon the stop lever 56 to adjust its angular relation relative to the rocker arm 57. It will be noted that the rocker arm cam 60 is effective to cause the rocker arm 57 to depress the holding pin 51 for slightly more than one-half revolution of the main shaft 21.

The upper part of the head frame 7 carries a pair of feed drums. One of these feed drums

feeds the socket members in a proper upright position and the other of the feed drums feeds the cap members properly positioned. Socket feed drum 62 (Figs. 3 and 4) feeds the socket members. The socket members are fed into this feed drum from a feed hopper 64. This drum 62 is removably mounted upon a socket drum shaft 65 and is intermittently rotated by a ratchet 66 which is fixedly mounted on the shaft 65. This ratchet is intermittently operated by a thrust dog 67 (Figs. 10, 3, 4, and 10). This thrust dog 67 is mounted on an arm 68 fixedly secured to oscillate with a short shaft 40 to which the main lever 37 is anchored by an anchor stud 69, so that each time the main lever 37 is oscillated, the thrust dog 67 engages and pushes forward the notches of the ratchet 66. As the feed drum 62 is intermittently rotated, socket members within this fed drum are tumbled about and tend to slide toward the face of the drum.

In order that the socket members may be properly positioned for further operations, it is necessary that the stems of the socket members shall be fed in an outward position relative to the rim of the drum 62. This desirable and necessary operation is accomplished by the utilization of an auxiliary member comprising a ring (Figs. 12, 13, 14, and 15) mounted upon the face edge of the drum 62. The face of the drum 62 is provided with guide grooves 70. These guide grooves lead to escape exits 71 for the socket members. These escape exits are in the separate ring 72 which is mounted upon the face edge of the feed drum 62. By this construction, it will be observed that the socket members 74 can only escape from the feed drum 62 with the stems of the socket members extending toward the central axis of the machine frame. The socket members, after escaping from the drum 62, slide down a runway 75 (Figs. 1, 2, and 4). This runway leads to a socket feed slide bar 76 (Figs. 26 to 30). One side wall of the end of the runway comprises a removable end 77, which may be easily removed in case of injury should a defective socket become caught in the mechanism. The bottom of the slide bar carrier adjacent the outlet of the socket runway is provided with a recess 78 (Figs. 18, 20, and 21) which has an inclined surface 79 leading toward the forward end of the slide-way for the slide bar. Sockets 74 coming down the runway 75 slide into the recess 78 and remain in this position until they are carried forward by the socket feed slide.

The main shaft 21 carries an eccentric 80 fixedly secured to the main shaft (Figs. 6, 8, and 9). A thrust arm 81 is mounted on the eccentric 80. This thrust arm is provided at its upper end with a guide-way for a slide block 82 through which a stub shaft 84 extends. The slide block 82 is normally held against an adjustable stop 85 by a coil spring 86. The stub shaft 84 is connected with an arm 87 of a bell crank member mounted on the slide operating shaft 30. The other arm 88 of the bell crank member carries a tension spring 89, which is connected with a swinging link 90 that is loosely mounted to rotate about the shaft 30 at one end and is connected with a slide block 91 at the other end. The slide block 91 is vertically slideable upon a thrust pin 92 on the slide bar 76. The arm 88 of the bell crank at its outer end is provided with a thrust face 94, and the arm 87 of the bell crank being in the form of an inclosing hood is provided with an opening 95 (Fig. 3) through which the adjustable stop 85 may be accessible. The tension spring 89 nor-

- 5 mally holds the swinging link 90 against the arm 88 of the bell crank as is illustrated in Figs. 6 and 8. If a deformed or imperfect socket member jams the slide bar 76 so that it cannot move, the 10 tension spring 89 will be stretched as indicated in Fig. 9 without injury to the parts. If on the return movement of the slide bar 76, any unusual resistance occurs, the spring 86 will be slightly compressed.
- 10 Referring now to Figs. 26 to 30 inclusive, a socket member 74 is fed into the recess 78 in the path of the slide bar 76. This recess will hold only 15 one socket so that the succeeding sockets are blocked in the end of the runway 15. The forward end of the slide bar is provided with a notch 96 in the path of which stands the stem of the socket member 74. A socket holding pawl 97 is provided with a head member 98 and a plate like body portion 99 which carries flat pin 100.
- 20 This flat pin is movable in the recess 101 in the slide bar 76 and is normally urged toward the rear of this recess by a coiled spring 102. A stop pin 104, mounted stationary in the bed plate 105 for the slide bar 76, is adapted to pass through 25 a groove 106 in the under side of the slide bar 76 and to engage the end of the body 99 when the parts are in normal position as indicated in Fig. 26, and thereby move the holding pawl 97 away from the notch 96 to permit the stem of a socket member 74 to be positioned between these two members. At the end of the movement of the slide bar 76, in moving from the front of the machine back to its normal position as illustrated 30 in Figs. 6 and 26, the slide bar 76 contacts with 35 a stop pin 103, thereby stopping the movement of this bar, and also stopping the swing of the bell crank 87-88. The continued movement of the eccentric 80 forces thrust arm 81 upwardly. During this time, the coil spring 86 contracts and this 40 operation provides a dwell equivalent to about 35° rotation of the main shaft, during which time a socket member 74 may come into position between the jaws 96 and 98. This dwell is of substantial importance where the machine is being operated 45 rapidly wherein one cycle of operations quickly follows another.
- 50 It will be noted from Figs. 6, 8, and 25 that the head 96 of the pawl 97 is wedge shaped. It will be also noted in Fig. 8 that this wedge shaped 55 head passes the riveting position. The purpose of the wedge shape on the head 97 is to permit this member to pass under work which is positioned at the riveting station to receive rivets. A blunt head would force the work aside and the operator would be disturbed during rapid operations of riveting. As soon as the slide bar 76 is moved toward the front of the machine, by the swing of the swinging link 90, the coil spring 102 causes the holding pawl 97 to move toward the 60 notch 96 and thereby clamp the stem of the socket member 74 between the notch and the pawl. At the same time, a guide pin 107 on the slide bar 76 enters an opening 108 in the head 98 of the holding pawl 97 to maintain the proper 65 relation of the parts. The slide bar 76 is moved forward to position the socket member 74 directly over the socket holding pin 51 which has been withdrawn below the surface of the anvil 49 as the slide bar 76 is moved forward. As soon 70 as the socket reaches this position, the rocker arm 57 operates to permit the spring 54 to raise the holding pin 51 into the opening in the socket 74 so that the socket is now securely set over the holding pin 51. The travel of the slide bar 75 76 is adjustable by the adjustable stop 85 in

order to position the socket 74 accurately over to pin 51. As the machine continues to operate, the eccentric 80 through the bell crank 87, 88, and the swinging link 90 pulls the slide 76 away from the front of the machine. The holding 5 pawl 97 drags over the socket on the pin 51 and compresses the coil spring 102 until the socket holding pawl 97 escapes from the socket on the holding pin 51. As soon as this happens, the spring 102 snaps the holding pawl back in 10 position on the end of the slide bar 76 with the guide pin 107 in the guide opening 108.

Figs. 29 and 30 indicate a slight modification of the holding pawl in that the guide pin 107 and the opening 108 are replaced by an inclined 15 surface 109 on the end 76 and an inclined surface 110 on the head of the holding pawl. The spring 102 causes these inclined surfaces to slide one upon the other until the inner face of the holding pawl contacts with the side face on the slide 20 bar. The operation of the modification as shown in Figs. 29 and 30 is the same as that previously described relative to the construction shown in Figs. 26, 27, and 28.

The feed mechanism for the cap comprises a 25 cap feed drum 111 (Figs. 1, 2, 3, and 4) which is removably mounted on a drum shaft 112 that rotates in a bearing 114 in the head frame 7. The inner end of this shaft 112 carries a feed ratchet 115 (Fig. 10) which is engaged by a pull ratchet 30 pawl 116. This ratchet pawl 116 is mounted on an arm 117 fixedly secured to the shaft 40 for the main lever 37. As the main lever 37 oscillates, the arm 117 swings to cause the ratchet pawl 116 to engage the ratchet 115 and rotate 35 the drum shaft 112 step by step. The rotation of the drum shaft causes caps fed into the drum 111 by the hopper 118 to be tumbled about in the cap feed drum 111. The feeding edge of this drum 111 (Figs. 16 and 17) is provided with exit 40 pathways 119. In the center of each pathway 119 is a conical projection 120 comprising the head of a stud set in the edge of the drum. A groove 121 is provided in the facing 122 opposite the path of the conical heads 120. Baffle plates 45 124 are also provided within the body of the drum 111 to loosen up the mass of caps within the drum as the drum rotates. These caps 125 are oval on the top and are provided with an opening on the opposite side. The studs 120 50 present obstacles to the escape of caps having the tops thereof in contact with the studs, but permit caps having the open sides toward the studs to slide over the studs into the groove 120 and then slide off the studs into the feed groove 55 126. Caps in the feed groove 126 slide down the cap runway 127 to the cut-off feed bar 128, which feeds caps one at a time from the runway 127 into the terminal guides 129, at each operation 60 of the machine.

This cut-off feed 128 is reciprocated by a spring member (Fig. 2) 130 which is carried upon a lever 131 pivoted in the main frame. The upper end of this lever 131 is provided with a stud 132, which stud extends between bifurcated arms 134 65 comprising a continuation of the arm 117 (Fig. 10) which operates the ratchet pawl for the cap drum shaft. During each cycle of operations of the machine, the bifurcated arms 134 swing the lever 131 to operate the cut-off 128 to release 70 one cap 125 from the runway 127 into the terminal guides 129. The terminal guides 129 are normally in contact with a spring arm cup 135 (Fig. 4) which comprises a pair of spring arms 136 and 137, each of which carries a half portion 75

of the cup member 135. This spring arm cup, which is adapted to hold a single cap, is positioned directly over the socket holding pin 51 and holds a cap directly beneath the setting head 48 carried by the plunger 45. The spring arms 136 and 137 are carried by a vertical slideable cup bar 138 mounted to slide in bearings in the head frame 7. This cup bar 138 is normally held up by a coiled spring 139 to bring the cup 130 into contact with the terminal guides 129. The coiled spring 139 has one end anchored to the head frame 7 and the other end anchored to the cup bar 138. An adjustable stop 140 limits the downward movement of the cup bar 138.

15 As the machine operates, a cap resting in the cup 135 is directly over a socket on the holding pin 51 in the path of the descending setting head 48. The downward movement of the setting head 48 carries the cup bar 138 downward 20 against the action of the coil spring 139 until the movement of the cup bar 138 is stopped by a stop 140. The continued descent of the plunger 48 causes the spring arms 136, 137 to swing outwardly (Fig. 6) to release the cap when it is 25 in position directly over the end of the socket on the socket pin 51. The continued movement of the setting head 48 applies pressure to the positioned cap, thereby expanding the upper end of the socket member within the cap and locking the same in position therein so that the socket 74 is securely locked within the cap 125 which is tightly seated against the material 141, thereby completing the operating cycle of the machine.

30 35 The adjustable eccentric stud 38 may be turned to adjust the limit of travel of the plunger 45 and the setting head 48, so that the effective pressure on the cap 125 may be regulated and in this way, the operation of the machine may be 40 adjusted for various sized caps and heights of sockets, or it may be adjusted to control the degree of flattening of the upper end of the sockets.

It will be observed that in the operation of the machine, a socket is fed from one side of the machine to arrive at the anvil in an upright position where it is held by the socket pin in the center of the anvil, and that a cap is fed from the other side of the machine in an upright position with the opening of the cap downward so that the cap is set down upon the upper end of the socket and the plunger continues its downward descent to apply pressure to crush or flatten the upper end of the socket and expand the same within the cap, thereby locking the parts 55 together.

Having described my invention, I claim:—

1. In a machine of the class described comprising a pedestal frame, an anvil on said frame, a head frame mounted on said pedestal frame, means to feed sockets downwardly to a socket feed slide so that said sockets reach said socket feed slide in an upright position, a socket feed slide for positively holding one of said sockets and moving the same forwardly to position the same over said anvil, means to hold said socket in position on said anvil when the said socket is released from said slide, feed mechanism to feed a cap upright over said socket on said anvil, and plunger means adapted to apply pressure to said cap and said socket to expand said socket within said cap and lock said cap and socket member together.

2. A machine of the class described comprising

ing a frame, an anvil, socket feed mechanism to feed sockets one at a time to said anvil, a holding pin for said sockets at said anvil, a rocker arm, a stop lever pivoted on said arm and engaging said pin, a cam to operate said arm and said lever to remove said pin from the passageway of a socket when a socket is being positioned at the anvil, a spring operative on said pin to insert said pin within a socket to hold said socket over said anvil during riveting operations, and means to expand said socket to rivet the same in place.

3. In a machine of the class described comprising a frame, an anvil on said frame, means to feed sockets one at a time to said anvil, a socket holding pin mounted to be reciprocated through said anvil, a rocker arm, a stop lever pivoted on said arm and engaging said pin to lower the same, a spring to raise said pin, and means to change the normal angular relation between said arm and said lever, to adjust the effective length of the path of reciprocation of said pin.

4. In a machine of the class described comprising a frame, an anvil on said frame, means to feed sockets one at a time to said anvil, a socket holding pin mounted to be reciprocated through said anvil, a spring to urge said pin upward, positively operated means to draw said pin downward, and means to adjust the upward limit of movement of said pin.

5. A machine of the class described comprising a socket feed mechanism adapted to feed socket members to a slide carrier, means on said slide carrier to hold a socket member and to move the same to a riveting station, an anvil at said riveting station, and means to hold said socket in position at said riveting station when said slide carrier is withdrawn.

6. A machine of the class described comprising a frame, socket feed means to feed sockets with the stems thereof upright, a slide member adapted to engage and hold a socket and transport the same to a riveting station, an anvil at said riveting station, and means comprising a socket pin adapted to enter a socket and hold the same over said anvil when said slide is withdrawn.

7. In a machine of the class described, a frame, means carried by said frame to feed sockets with the stems thereof upright, a socket slide comprising a body portion and a gripping jaw, means to cause said gripping jaw to engage a socket and clamp the same against said body portion, means to move said slide to transport said socket to a riveting station, an anvil at said riveting station, a socket holding pin, means to cause said socket holding pin to be brought into engagement with the opening in said socket when said socket is positioned at said anvil to hold said socket over said anvil, and means to compress said socket against said anvil to rivet the same.

8. In a machine of the class described, the combination of a frame; a socket feed mechanism on said frame and adapted to feed sockets with the stems upright; a socket feed slide; and means to reciprocate said slide, said means comprising a bell crank, an arm mounted on the axis of said bell crank, and a spring operatively connecting said arm and said bell crank whereby said spring may yield should said slide encounter resistance thereby obviating breakage.

JULIUS GUALTIERE.
